(57) **CLAIM**

The ornamental design for a water heater, as shown and described.

DESCRIPTION

FIG. 1 is a perspective view of a water heater in accordance with a first embodiment;

FIG. 2 is another perspective view of the water heater shown in FIG. 1;

FIG. 3 is a view of the water heater shown in FIG. 1 from the front;

FIG. 4 is a view of the water heater shown in FIG. 1 from the rear;

FIG. 5 is a view of the water heater shown in FIG. 1 from the left;

FIG. 6 is a view of the water heater shown in FIG. 1 from the right;

FIG. 7 is a view of the water heater shown in FIG. 1 from the top; and

FIG. 8 is a view of the water heater shown in FIG. 1 from the bottom.

FIG. 9 is a perspective view of a water heater in accordance with a second embodiment;

FIG. 10 is another perspective view of the water heater shown in FIG. 9;

FIG. 11 is a view of the water heater shown in FIG. 9 from the front;

FIG. 12 is a view of the water heater shown in FIG. 9 from the rear;

FIG. 13 is a view of the water heater shown in FIG. 9 from the left;

FIG. 14 is a view of the water heater shown in FIG. 9 from the right;

FIG. 15 is a view of the water heater shown in FIG. 9 from the top; and

FIG. 16 is a view of the water heater shown in FIG. 9 from the bottom.

FIG. 17 is a perspective view of a water heater in accordance with a third embodiment;

FIG. 18 is another perspective view of the water heater shown in FIG. 17;

FIG. 19 is a view of the water heater shown in FIG. 17 from the front;

FIG. 20 is a view of the water heater shown in FIG. 17 from the rear;

FIG. 21 is a view of the water heater shown in FIG. 17 from the left;

(Continued)

FIG. 22 is a view of the water heater shown in FIG. 17 from the right;

FIG. 23 is a view of the water heater shown in FIG. 17 from the top; and,

FIG. 24 is a view of the water heater shown in FIG. 17 from the bottom.

The broken lines in the figures show portions of the water heater that form no part of the claimed design.
